Dec. 14, 1926.

D. L. KNIGHT

1,610,861

COMBINATION NAPKIN HOLDER AND PLACE MARKER

Filed March 31, 1924

FIG. 1.

FIG. 2

FIG. 3

DAYE L. KNIGHT

INVENTOR.

BY

John L. Knight

ATTORNEY.

Patented Dec. 14, 1926.

1,610,861

UNITED STATES PATENT OFFICE.

DAYE L. KNIGHT, OF KANSAS CITY, MISSOURI.

COMBINATION NAPKIN HOLDER AND PLACE MARKER.

Application filed March 31, 1924. Serial No. 703,069.

It is the object of my invention to provide a device that will hold a napkin and at the same time hold a visiting card or a place marker for diners at a dinner table.

It is the further object of my invention to provide a place marker and napkin holder combined, the napkin being on one side and the place marker, or card on the reverse side.

It is the primary object of my invention to so construct the device that the card cannot slip out with ordinary use.

For illustrating my invention the accompanying drawings, in:

Figure 1 shows a perspective view of the napkin holder, and place marker.

Fig. 2 shows a vertical view of the holder.

Fig. 3 shows a cross section of the holder.

In Fig. 1 number 1 is a rectangular piece of metal, preferably highly polished and plated; number 2 is a spring made from one piece of metal so curved that said spring 2 exerts a pressure on one side sufficient to hold a card against the side of the rectangular piece 1 and allowing ample room on the reverse side for the purpose of holding linen, 25 such articles as napkins and the like.

Having thus described the invention, what I claim as new and desire to secure Letters Patent, is:

A device of the character described, comprising a flat, rigid plate, having spaced apertures adjacent one edge, and a keeper formed from a single piece of wire bent into the form of a double U-shaped body, having connecting shanks, the shanks being fitted in 35 the aperture of the plate to attach the keeper thereto and the separate U members of the keeper body being located on opposite sides of the plate and free therefrom beyond the shanks. 40

In testimony whereof I affix my signature.

DAYE L. KNIGHT.